JACOB CHRISTIAN HANSEN-ELLEHAMMER, OF COPENHAGEN, DENMARK.

FUEL-SUPPLY APPARATUS FOR EXPLOSION-MOTORS.

1,189,688.

Specification of Letters Patent.

Patented July 4, 1916.

Application filed February 15, 1915. Serial No. 8,334.

To all whom it may concern:

Be it known that I, JACOB CHRISTIAN HANSEN-ELLEHAMMER, a citizen of the Kingdom of Denmark, residing at 119 Istedgade, Copenhagen, in the Kingdom of Denmark, have invented certain new and useful Improvements in or Relating to Fuel-Supply Apparatus for Explosion-Motors, of which the following is a specification.

10 This invention refers to fuel supply apparatus for explosion motors, in which the liquid fuel, before its mixture with the combustion air, is continuously transformed into vaporous fuel, superheated fuel vapor, or gas, and in which either a mixture of two or more different kinds of fuel or one kind of fuel can be used, means being provided to change directly from this to another lighter or heavier fuel-oil.

20 This invention differs essentially from those devices (certain carbureters), in which the vaporization of the fuel-oil takes place by heating in the very air sucked in by the motor. According to this invention, the vaporization of the fuel-oil takes place independently of the air, the fuel oil being mixed with the air after its vaporization. Thus the air can be directly sucked in as cold air through an automatic valve, which, with relation to the feed-pipe of the motor, is disposed parallel to the fuel-oil vaporizer. This does not prevent, however, that a small quantity of air may be sucked into the vaporizer together with the fuel-oil, in order 35 to facilitate the passage of the oil through the vaporizer.

40 Furthermore, this invention essentially differs from other devices of this kind in which floats, pumps, or the like, are used, in that the effect of the apparatus here set forth depends directly upon the suction of the motor, which actuates both the air-valve and (parallel thereto) the vaporizer, causing the fuel-oil to be sucked into the vaporizer, and 45 the fuel-vapor to be sucked from there to the mixing chamber with the air.

The accompanying drawings show, by way of example, one form of construction of the said apparatus, which may be directly 50 attached to an ordinary automobile or motor boat.

Figure 1 represents an elevation, partly in section of one embodiment of this apparatus. Fig. 2 represents a transverse section of the 55 vaporizer on line 2—2 of Fig. 1. Fig. 3 represents a vertical transverse section on line

3—3 of Fig. 1 showing the duplex cock for controlling and varying the plural feed supply.

The air-valve 1, which is furnished with a short spring 2, the tension of which rapidly increases during the opening movement, is disposed in a valve-casing 3, which in a suitable manner, not shown on the drawing, is connected with the motor or its various cylinders, and is also connected with the vaporizer by means of a pipe 4, which opens into the valve-casing above the valve 1. The vaporizer consists of a number of pipes 5 disposed in a circle, a central pipe 6, and two collecting chambers 7 and 8, the vaporizer being entirely or partially disposed in the exhaust pipe 9 of the motor. In the central pipe 6, which projects through the collecting chamber 7, a pipe 10 opens which, by means of a junction box 11, is connected with pipes 12 and 13 rising from two fuel tanks 14 and 15. These pipes are regulated together by a hand-actuated member such as a cock 16, with two ways 17 and 18 bored at an angle to each other. The mouth 19 of the pipe 10 opening into junction box 11 has dimensions corresponding to those of the narrowed opening usual in fuel-oil suction-pipes. The pipe 6, surrounding the other end of the pipe 10 is provided with fine air-openings 20.

The motor is started by means of benzin, or some other light volatile oil fed, for instance, from the tank 14. The cock 16 is 90 then turned so that the conduit 17 is open and the conduit 18 is entirely closed. Through the turning of the motor-shaft, the suction caused thereby will actuate the air-valve 1, which will, however, only be slightly 95 opened, owing to the resistance of the spring 2 and the slow speed, and through the pipe 4, the vaporizer 5—8, the pipe 10 and the pipe 11, will cause the liquid to rise in the pipe 10 and flow into the vaporizer. At the same time a slight quantity of air will be sucked in through the holes 20 to atomize the liquid in the pipe 6. After having been sucked through the chamber 8 and distributed in the pipes 5, thereby decreasing its 100 speed and greatly increasing its surface, the liquid will readily vaporize under the existing low pressure, so that an explosive mixture can be formed inside the casing 3. Ignition then takes place and the motor is 110 started. After only a few strokes (lasting only a few seconds) the exhaust through the

pipe 9 will have considerably warmed the pipes 5, and if then the cock 16 be turned so that the conduit 18 is open and the conduit 17 is nearly closed, the suction 5 will also and to a higher degree influence the less volatile and heavier fuel-oil, petroleum, crude oil, or the like, in the tank 15, so that a mixture poor in benzin is sucked into the hot vaporizer, where it practically 10 acquires the same vaporizing capacity (owing to the heat of the vaporizer) as that of the benzin when the vaporizer was cold. After a short time the cock 16 can be turned so that the conduit 17 is entirely closed, and 15 only the conduit 18 is left open, and then the motor will continue working, consuming only the fuel-oil in the tank 15. By simply turning the cock 16, the driver may now at any time change from the consumption 20 of only heavy, slightly volatile fuel-oil to the consumption of the light volatile oil, or vice versa, or to the consumption of a mixture of both kinds of fuel-oil in a desired proportion, without in any way interfering 25 with the running of the motor. Owing to the nature and adjustment of the spring 2, the supply of fuel-oil is regulated automatically, so that, no matter what is the number of revolutions, the proportion of the mixture 30 of air and fuel-oil is always correct. Notwithstanding the ready vaporization of the liquid in the vaporizer, the suction will always remain constant in the pipes 10 and 12 or 18, since the vaporization takes place 35 during the transition from a smaller space (the pipe 6 and the collecting chamber 8) to a much greater space (the pipes 5, the collecting chamber 7 and the pipe 4), so that it is not accompanied by any perceptible increases in pressure.

I claim:

1. In a fuel supply apparatus for explosion engines the combination of a valve casing for a motor cylinder, an automatic intake air valve therein, a vaporizer, a vapor feed pipe connecting said valve casing and vaporizer, a fuel mixing chamber, a pipe connecting said mixing chamber with said vaporizer, a plurality of fuel tanks, pipes connecting said tanks with said fuel mixing chamber, and a unitary controlling device for the joint regulation of the supply of

plural fuels passing from said plural tanks to said fuel mixing chamber.

2. In a fuel supply apparatus for explosion engines the combination of a valve casing for a motor cylinder, an automatic intake air valve therein, a vaporizer, a vapor feed pipe connecting said valve casing and vaporizer, a fuel mixing chamber, a pipe connecting said mixing chamber with said vaporizer, a plurality of fuel tanks, pipes connecting said tanks with said fuel mixing chamber, and a unitary controlling device for the joint regulation of the supply of plural fuels passing from said plural tanks to said fuel mixing chamber, said pipe connecting the valve casing and vaporizer being of larger diameter than said pipe connecting said mixing chamber with the vaporizer.

3. In a fuel supply apparatus for explosion engines the combination of a valve casing for a motor cylinder, an automatic intake air valve therein, a vaporizer having an enlarged area at its point of discharge and a small area at its point of intake, a vapor feed pipe of larger diameter connecting the large end of said vaporizer with said casing, a supply chamber, and a pipe of small area connecting said chamber with the small end of said vaporizer.

4. In a fuel supply apparatus for explosion engines the combination of a valve casing for a motor cylinder, an automatic intake air valve therein, a vaporizer having an enlarged area at its point of discharge and a small area at its point of intake, a vapor feed pipe of larger diameter connecting the large end of said vaporizer with said casing, a supply chamber, and a pipe of small area connecting said chamber with the small end of said vaporizer, said last named pipe projecting into the intake end of said vaporizer and having a series of peripheral perforations within said end.

In testimony that I claim the foregoing as my invention, I have signed my name in presence of two subscribing witnesses.

JACOB CHRISTIAN HANSEN-ELLEHAMMER.
